UNITED STATES PATENT OFFICE.

CLIFTON REEVES, OF TRENTON, NEW JERSEY.

STEAM-VALVE.

1,271,938.

Specification of Letters Patent. Patented July 9, 1918.

Application filed March 13, 1915. Serial No. 14,051.

To all whom it may concern:

Be it known that I, CLIFTON REEVES, of Trenton, in the county of Mercer and in the State of New Jersey, have invented a certain new and useful Improvement in Steam-Valves, and do hereby declare that the following is a full, clear, and exact description thereof.

My invention relates particularly to valves 10 designed to be applied to steam engines.

The object of my invention is to provide a steam valve in which the valve ring on the piston valve is constantly maintained against its seat by the use of the elasticity 15 of the valve ring, also through the aid of pressure exerted by the steam itself. Another object of my invention is to provide a construction of this character in which the parts are few in number and the form 20 of construction simple so that there will not be a large number of parts to get out of order, and so that any repairs or replacements can be readily made. Another object of my invention is to provide a construction 25 of this kind in which the parts of the valve ring cannot wear the bridge faster than the main body of the sleeve, which is arranged to receive a piston valve.

While my invention is capable of embodiment in many different forms, for the purpose of illustration I have shown only one form thereof in the accompanying drawings, in which,

Figure 1 is a vertical section of a steam 35 engine equipped with my valve; and

Fig. 2 is a vertical section of my piston valve.

In the drawings I have shown a steam cylinder 1, having a piston 2 therein, said 40 steam cylinder having cylinder heads 3 and 4. The cylinder 1 is furthermore provided with a valve chamber 5, which communicates with the cylinder 1 by means of ports 6 and 7. The ports 6 and 7 are arranged 45 to communicate with openings 8 and 9 in sleeves 10 and 11, which are contained in the valve chamber 5, and which are arranged to receive a piston valve 11^a, having at its ends rods 12 and 13 adapted to be 50 guided by heads 14 and 15 on the ends of the valve chamber. In each of the sleeves 10 and 11, the openings 8 and 9 are arranged at intervals around the sleeves with bridge portions 10^a separating the portions 55 of the opening in the two sleeves. The reciprocation of the piston valve 11^a is so effected that steam is admitted from the steam chamber 5 first to the port 6 and then to the port 7, so as to be conveyed ultimately to opposite ends of the cylinder 1. 60 When steam is being admitted to the port 6, the port 7 is in communication with the exhaust chamber 16, and when steam is being admitted to the port 7, the port 6 is in communication with the exhaust chamber 65 17. The piston valve 11^a is provided opposite each of the ports 6 and 7 with a piston, each of which is comprised of two end members 18 and 19 having annular shoulders 20 and 21 to receive a ring 22. Each of the 70 rings 22 is provided with annular recesses 23 and 24 to receive piston rings 25 and 26 and the piston rings 25 and 26 have recesses 27 and 28 to receive a central piston ring 29. A port 30 passes through each of the end 75 members 19 to communicate with the recess 24 beneath the piston ring 26. Furthermore, each of the central piston rings 29 has a port 31 to equalize the pressure on opposite sides of said piston ring. 80

In the operation of my invention the piston valve 11^a is reciprocated in the usual way, thus admitting steam first to the port 6 and exhausting steam from the port 7 and then admitting steam to the port 7 and exhausting steam from the port 6, so as to reciprocate the piston 2. During the reciprocation of the piston valve 11^a steam is admitted through the port 30, thus forcing the piston rings 26 outwardly against the 85 sleeves 10 and 11, which cause the central piston ring 29 to be moved outwardly owing to the fact that the several piston rings on each of the pistons are interengaged with one another. The action of the steam in this 90 manner is to greatly supplement the outward pressure produced by the elasticity of the rings themselves. If it were not for the central piston rings 29, the piston rings 25 and 26 would wear the bridge portions 10^a 100 faster than the main bodies of the sleeves 10 and 11, so that the rings 25 and 26 would finally catch in the bridge portions 10^a and become broken. By the presence of the central piston rings 29, however, the more rapid 105 wear of the bridge portions 10^a is avoided, inasmuch as while the piston rings 26, for example, are opposite the bridge portions 10^a, the central piston rings 29 will be supported upon the body portions of the sleeves 110 10 and 11, thus preventing said bridge portions 10^a from wearing faster than the body

portions of the sleeves 10 and 11. In the 5 operation of the piston valve, should a sudden shot of water enter the valve chamber, the piston rings will all yield together, thereby relieving the pressure and permitting the escape of a portion of the water so as to avoid damage to the parts. This 10 will be readily seen from the fact that a constant pressure of this kind on the rings 29 will result also in a compression of the rings 25 and 26.

While I have described my invention above in detail, I wish it to be understood that many changes may be made therein 15 without departing from the spirit of my invention.

I claim:

1. In combination a piston valve comprising two side rings, laterally projecting shoulders on the adjacent sides of said rings and a central valve seat engaging ring supported upon said shoulders to permit free outward movement of said central ring, and a valve seat comprising a cylindrical sleeve having 25 a peripheral port opening therein, said central ring engaging a full portion of said sleeve when either of the side rings covers the port opening.
2. In combination, a piston valve having 30 two side rings recessed on their adjacent sides, a central valve seat engaging ring supported in said recesses in such a manner as to permit independent outward movement of one of the side rings relative to the other, and a valve seat comprising a cylindrical sleeve having a peripheral port opening therein, said central ring engaging a full

portion of said sleeve when either of the side rings covers the port opening.

3. In combination, a piston valve having 40 two side rings recessed on their adjacent sides, a central valve seat engaging ring supported in said recesses in such a manner as to permit independent outward movement of one of the side rings relative to the other, and a valve seat comprising a cylindrical sleeve having a peripheral port opening therein, 45 said central ring engaging a full portion of said sleeve when either of the side rings covers the port opening, one of said side rings being provided with means for submitting the under surface thereof to the direct action of the steam.

4. In combination, a piston valve having 55 two side rings recessed on their adjacent sides, a central valve seat engaging ring supported in said recesses in such a manner as to permit independent outward movement of one of the side rings relative to the other, and a valve seat comprising a cylindrical 60 sleeve having a peripheral port opening therein, said central ring engaging a full portion of said sleeve when either of the side rings covers the port opening, the central ring being provided with a port to 65 equalize the pressure on the upper and lower surface thereof.

In testimony that I claim the foregoing I have hereunto set my hand.

CLIFTON REEVES.
